J. W. ELLIS

GREASE GUN

Filed June 9, 1924

Fig. 1.

UNITED STATES PATENT OFFICE.

JOHN W. ELLIS, OF BARNESVILLE, OHIO, ASSIGNOR TO THE WATT MINING CAR WHEEL COMPANY, OF BARNESVILLE, OHIO, A CORPORATION OF OHIO.

GREASE GUN.

Application filed June 9, 1924. Serial No. 718,931.

This invention is a novel grease gun especially adapted for use in connection with lubricating mine car wheels but also applicable for use in lubricating other mechanisms or parts where a forced feed lubrication is desired.

The object of the invention is to provide a novel grease gun which is readily adapted for use with many different kinds of oilers, or inlets of the grease containers in the object to be lubricated, and can be readily operated by hand.

I will explain the invention with reference to the accompanying drawings which illustrate the grease gun, and manner of using the same, to enable others to adopt and use the invention; and the claims summarize the essentials of the invention and the novel features and novel combinations of parts for which protection is desired.

In said drawings:

Figure 1 is a side view of the complete gun, with part of the casing broken away to show the interior construction, the parts of the gun being in position when no grease is flowing through the gun.

Figure 2 is a longitudinal section through the gun showing the parts in position when the grease is being applied through the gun.

Figure 3 is an enlarged view of the outlet end of the gun.

As shown in the drawings, the gun comprises an outer casing which is preferably composed of assembled parts, to wit: a barrel 1, an outlet head 2 at one end of the barrel, an inlet head 4 at the other end of the barrel; and a connecting piece 3 attached to one end of the barrel and connecting the same with the inlet head 4. One or more of these parts might be formed integral but for convenience I preferably make them separately and connect them together as hereinafter described. Upon the barrel 1 adjacent the connecting piece 3 is mounted a rotatable but not longitudinally movable sleeve 5 for a purpose hereinafter described.

The head 4 has an axial bore which is internally threaded at the outer end 4^a for engagement with a pipe or hose section 10 of any suitable kind which is connected to any suitable source of supply of lubricant under pressure, not shown. The inner end of the bore in head 4 is enlarged as at 4^b and

also internally threaded to engage an externally threaded nipple 3^b on the adjacent 55 end of the connecting piece 3.

The piece 3 has an internal bore which is divided by a partition 3^a through which is an opening for the passage of a slidable tube 7 hereinafter described. The inner end of 60 connecting piece 3 has an externally threaded nipple 3^c which engages internally threaded portion 1^c in the adjacent end of the barrel 1, the piece 3 firmly connecting and aligning the barrel and the inlet head. 65

The barrel 1 is provided with an internal bore through which the tube 7 extends, said tube preferably having a slidable close fit in the barrel and in piece 3. The barrel is provided with a longitudinal slot 1^a 70 through which projects a pin or screw 7^a, attached to the tube 7, said pin permitting longitudinal play of the tube in the barrel but preventing rotation thereof. The other end of the barrel is connected with the outlet 75 head 2 by any suitable means.

Preferably the head 2 has a sliding fit on the outer end of the barrel, and may be fastened to the barrel, in the desired adjusted position, by means of a set screw 2^s, or by 80 other suitable means.

The outer end of the head 2 is preferably adapted to engage and interlock with an oiling plug 8 fitted in the inlet end of the oil duct or chamber in the object to be lubricated. 85

The tube 7 extends through the barrel 1 and its opposite ends respectively project into the head 2 and into the head 4. The end of the tube 7 extending into the head 4 90 is preferably closed as shown; but the grease may enter this end of the tube through openings 7^c therein adjacent the closure 7^b.

A cylindric member 6 is preferably secured to the end of the tube 7 within the outlet head 2 by interengaging threads as shown. Said member 6 is approximately disk shaped and has a slidable fit in the bore of the head 2, and member 6 supports the inner end of the tube 7 within the head 2. Member 6 has at its outer side a projecting tubular extension or nozzle 6^a, and this extension 6^a and member 6 are axially bored as at 6^b. 95 100 105

In the drawings, I have shown an ordi-

nary so called "oiler" 8 which is externally threaded to engage internal threads in the bore or duct 9^a of the object 9 to be oiled; such oiler has an angular flange 8^a on its 5 outer end projecting slightly beyond the object 9; and said flange is adapted to be engaged by a bayonet shaped flange or slot 2^a on the outer end of head 2, so that the part 2^a can be readily engaged with the part 8^a 10 as shown in Figures 1 and 2, and when so engaged can not be pulled axially away therefrom, nor rotated relative thereto while engaged therewith. The oiler 8 has an axial bore having a shoulder 8^b at its outer end and 15 a pin 8^c at its inner end; and within the oiler is fitted a closing cap 8^d which is normally pressed outward by a spring 8^e interposed between the cap and the pin 8^c, so that normally the cap is seated against the 20 flange 8^a and prevents escape of oil from the duct 9^a and entrance of dust therein. The said cap can be pushed inward by the nozzle of an oil can when it is desired to supply oil to the duct 9^a. As the oiler 25 shown is a well known form of oiler, further description thereof is unnecessary.

The nozzle 6^a is adapted to be projected beyond the outer end of the outlet head 2 when the gun is in use, so that the part 6^a 30 may be entered into the oiler 8 as indicated in Figure 2, displacing the cap 8^d, therein, and allowing the oil or grease to enter the duct 9^a. The extremity of the nozzle 6^a 35 may be provided with lateral apertures or recesses 6^c, through which the oil can escape into the oiler 8, and through the latter into the duct 9^a of the object to be lubricated.

Preferably a washer 6^e is placed on the nozzle 6^a and abuts against the part 6. This washer 40 is adapted to form a practically grease tight joint between the outer end of the oiler and the disk or member 6 when the gun is in use, as indicated in Figure 2. A washer 4^e 45 may be placed in the bore of the inlet head 4, and contacted by the closed end 7^b of the tube 7 when the latter is retracted, as indicated in Figure 1, when the gun is not in use.

The tube 7 may be shifted longitudinally, 50 by any suitable means, to the retracted closed position indicated in Figure 1 or to the projected operative position indicated in Figure 2. Preferably I provide the sleeve 5 with a cam slot 5^a which is engaged by the 55 projecting end of the pin 7^a. The cam slot 5^a is of such pitch and length that by properly turning the sleeve the interengagement of the pin 7^a with slot 5^a will move the tube 7 to the closed position indicated in Figure 1; in which position the head 7^b of the tube abuts against the washer 4^e and forms a close joint therewith, so that no grease 60 can escape. In this retracted position of the tube the nozzle 6^a is retracted within 65 head 2. By turning the sleeve 5 in a reverse

direction, the tube 7 can be moved to the operative position indicated in Figure 2; in which position (assuming that the head 2 has been previously interlocked with the oiler 8 as indicated in Figures 1 and 2) the nozzle 6^a will enter the oiler (forcing back the cap 8^d and compressing spring 8^e) and permit grease under pressure to flow from the supply pipe 10 through the tube 7 and nozzle 6^a into the duct 9^a of the part to be lubricated. The sleeve 5 is preferably polygonal to facilitate turning thereof, but may be of any desired contour.

From the foregoing it will be seen that when it is desired to use the gun, the head 2 is engaged with the oiler while the tube 7 is in retracted position (Fig. 1); then the tube 7 is projected, as indicated in Figure 2, and grease will flow from the supply pipe 10 through the gun into the object to be lubricated. When the head 2 is engaged with the oiler, the tube 7 can be readily moved to cause the nozzle 6^a to displace cap 8^d in the oiler by simply turning the sleeve 5, the cam slot 5^a greatly augmenting the power applied to the sleeve.

The ends of the cam slot 5^a are preferably deflected at such an angle to the axis of the sleeve that the pin 7^a will effectively lock or hold the tube 7 in either its retracted or projected position. When the tube 7 is retracted as in Figure 1, it is tightly closed and no grease will be lost. When the gun is in operation loss of lubricant is prevented by the close joint formed by the washer 6^e 100 between the part 6 and the oiler 8.

Oil may be supplied to pipe 10 by any suitable means not shown, forming no part of the present invention, such as a force pump or other supply of grease under pressure. When the grease gun is closed as shown in Figure 1, no grease can flow therefrom even if part 10 is connected to a grease supply under pressure, because the tube 7 is held in retracted position against the washer 4^e by the end of cam slot 5^a engaging pin 7^a (as shown in Fig. 1) which holds the tube securely until the sleeve is turned. By simply turning the sleeve 5 the tube can be moved to the left, whereupon the grease is permitted to flow, and grease will continue to flow through and from the gun until the reservoir 9 is filled, or the supply is cut off by retracting tube 7, by turning sleeve 5 to the position shown in Fig. 1. With this gun the operator does not have to hold the gun either when it is in open or closed position, if the gun is properly engaged with the oiler.

When the gun is in use and grease is flowing therethrough, the parts are in the position indicated in Figure 2, and there is a tendency of the grease to pass backward around the tube 7 and into the barrel 1 and up through the slot 1^a to the sleeve part 5. To prevent such leakage, a washer 1^b (see 130

Figure 2) is seated in a recess in the end of the barrel 1 and clamped therein by the nipple 3^e on the part 3.

While I have shown different parts of the gun connected by screw threads, I do not intend to limit myself to the use of screw threads, as such parts may be fastened together in any preferred suitable manner.

To enable the gun to be used with some forms of equipment or machines already in service the screw 2^s may be loosened and the outlet head 2 moved back until the nozzle 6^a is uncovered, and then the screw may be set. Then the nozzle can be inserted directly into the inlet of the chamber or object to which oil is to be supplied, while the gun is held by hand; without any interlocking between the part 2 and the object to which the grease is supplied. By the word "grease" I mean to include any kind of fluid or semi-fluid lubricant.

I claim:

1. A grease gun connection comprising a casing adapted to be connected at one end with a grease supply under pressure and having a nozzle at its other end adapted to be entered into the inlet of the object to be lubricated; a longitudinally movable member within the casing connected at one end to the nozzle; and manually operable means for longitudinally moving the member in the casing to retract the nozzle, said member being adapted when in one position to close the grease passage, and when in another position to project the nozzle and open the grease passage.

2. In a grease gun connection as set forth in claim 1, the means for moving the member comprising a pin connected with the member, and a rotatable sleeve mounted on the casing and having a cam slot engaging said pin.

3. A grease gun connection comprising a casing having a barrel; an inlet head at one end; and an outlet head at its other end; a longitudinally movable member within the casing and extending adjacent the inlet head and into the outlet head; manually operable means for moving said member said member being adapted in one position to close the inlet head to prevent the admission of grease and in another position to open the inlet head to permit the admission of grease; and a nozzle within the outlet head adapted to be entered into the grease inlet of the member to be lubricated.

4. In a grease gun connection as set forth in claim 3, the means for moving the member comprising a pin connected with the member, and a rotatable sleeve mounted on the casing having a cam slot engaging said pin, substantially as described.

5. A grease gun connection comprising a casing having a barrel; an inlet head at one end thereof adapted to be connected

to a supply of grease; and an outlet head at the other end of said barrel adapted to be detachably engaged with the grease inlet of the object to be lubricated; a longitudinally movable tube within the casing extended through the barrel adjacent the inlet head and into the outlet head and adapted in one position to close the inlet head and prevent the admission of grease, and in another position to open the inlet head to permit the admission of grease, and manually operable means for moving said tube, substantially as described.

6. In a grease gun connection as set forth in claim 5, the means for moving the tube comprising a pin connected with the member, and a rotatable sleeve mounted on the casing having a cam slot engaging said pin.

7. A grease gun connection comprising a casing having a barrel; an inlet head at one end thereof adapted to be connected to a supply of grease; and an outlet head at the other end of said barrel adapted to be detachably engaged with an oiler or closure at the grease inlet of the object to be lubricated; a longitudinally movable tube within the casing extended through the barrel adjacent the inlet head, and into the outlet head and manually operable means for moving the tube, said tube being adapted in one position to close the inlet head to prevent the admission of grease and in another position to open the inlet head to permit the admission of grease.

8. In a grease gun connection as set forth in claim 7, the means for moving the tube comprising a pin connected with the tube, and a rotatable sleeve mounted on the casing having a cam slot engaging said pin.

9. A grease gun connection comprising a casing having a barrel; an inlet head at one end thereof; an outlet head at the other end of said barrel; a longitudinally movable tube within the casing extended through the barrel adjacent the inlet head, and adapted in one position to close the inlet head to prevent the admission of grease and in another position to open the inlet head to permit the admission of grease; manually operable means for adjusting said tube; an outlet head; a member slidably mounted within the outlet head and connected with said tube; and a nozzle connected with the said member adapted to be entered into the grease inlet of the part to be lubricated.

10. In a grease gun connection as set forth in claim 9, the means for adjusting the tube comprising a pin connected with the tube, and a rotatable sleeve mounted on the casing having a cam slot engaging said pin.

11. A grease gun connection comprising a casing having a barrel; an inlet head at one end thereof adapted to be connected to

- a supply of grease under pressure; an outlet head at the other end of said barrel adapted to be detachably engaged with an oiler or closure at the grease inlet of the 5 part to be lubricated; a longitudinally movable tube within the casing extended through the barrel adjacent the inlet head and into the outlet head, and adapted in one position to close the inlet head to prevent the admission of grease and in another 10 position to open the inlet head to permit the admission of grease; a disk slidably mounted within the outlet head and connected with said tube; and a nozzle on the said disk within the outlet head and adapted to be entered into the grease inlet of the part to be lubricated. 15
12. In a grease gun connection as set forth in claim 11, means for adjusting the tube comprising a pin connected with the tube; and a rotatable sleeve mounted on the casing having a cam slot engaging said pin. 20

In testimony that I claim the foregoing as my own I affix my signature.

JOHN W. ELLIS.
